UNITED STATES PATENT OFFICE.

WILLIAM A. BRIGHTMAN, OF SULLIVAN, KENTUCKY.

EXTRACTOR FOR AUTOMOBILES.

Application filed May 6, 1926. Serial No. 107,224.

This invention relates to extractors and more particularly to an extractor of the windlass type by means of which a mired automobile may be readily removed from a 5 mudhole.

One object of the invention is to provide an extractor of the type specified which may be folded into a compact mass and readily transported from one place to another.

Another object of the invention is to provide the extractor with a winding drum for a pulling cable and guide rollers for the cable which are rotated from the winding 15 drum so that they may serve to feed the cable to the drum in addition to guiding movement of the cable.

Another object of the invention is to provide the extractor with a brace rod by means 20 of which it may be retained in an upright position when in use.

This invention is illustrated in the accompanying drawings, wherein

Figure 1 is a view showing the improved 25 extractor in side elevation;

Fig. 2 is a top plan view of the extractor when folded;

Fig. 3 is a view showing the extractor in end elevation.

The extractor forming the subject-matter of this invention is provided with a frame which is of a rectangular formation and formed in sections, indicated in general by the numerals 1 and 2. The upper and lower bars 3 and 4 are firmly secured to vertically disposed end bars 5 and bracing blocks 6 are disposed at the intersection of the end bars and upper and lower bars so that these bars will be braced and a strong frame thereby provided. At their inner or meeting ends the upper and lower bars of the frame sections are joined by hinges 7 so that the sections may be extended to an operative position, as shown in Figs. 1 and 3, or folded to the collapsed position shown in Fig. 2. It should also be noted that the upper and lower bars of one section carry hasps 8 which are adapted to be engaged with the staples or other equivalent keepers 9 carried by the companion bars of the other frame section and securely but releasably hold the sections in the extended operative position when wedges or other suitable fas-

teners are passed through the keepers. A recess 10 is formed in the inner end of each 55 upper and lower bar, and these recesses are lined by metal strips 11 which extend across the end faces of the bars at opposite sides of the recesses. The recesses of the companion bars register when the frame sections are in the extended position and form 60 bearings.

The drum 12 upon which the cable 13 is to be wound extends between the upper and lower bars of the frame and is provided 65 with a spur 14 with which an intermediate portion of the cable may be engaged. The cable may thus have its intermediate portion wound upon the drum and its end portions extended from the drum in opposite 70 directions and passed through openings formed in the end bars 5 of the frame. The upper and lower portions of the drum 12 are journaled in the bearings formed by the companion recesses 10 of the bars 3 and 4 75 and the portion of the drum which is rotatably mounted in the upper bearing is extended upwardly above the frame to provide a post 15 which terminates at its upper end in spaced arms 16. A crosshead 17 is secured 80 between the arms 16 by rivets or other suitable fasteners 18, and this crosshead extends from opposite sides of the post and is open at its ends in order to receive handle bars 19, by means of which the drum is to be 85 rotated. These handle bars may be of any desired length and since they may be removed from the crosshead 17 they will not be in the way when the frame is folded. The drum is formed with an axially extending 90 passage adapted to receive a bracing rod 20 which is formed of strong metal and of such length that its upper and lower ends will project from the upper and lower ends of the drum, as shown in Figs. 1 and 3. The 95 lower end of the rod 20 is tapered to form a penetrating point which may be held in engagement with the ground so that the frame will be retained in a vertical position. The 100 rod will, of course, be moved along the ground from one place to another as the cable is wound upon the drum.

In order to guide movement of the cable into and out of the frame each of the end 105 bars 5 has been provided with guide rollers

21 and 22. The rollers are provided with shafts 23 and 24 which are rotatably mounted by bearing brackets 25 and 26, and by referring to Fig. 3 it will be seen that the shaft 23 projects from one side of its roller 21 and carries a pinion 27 which meshes with a pinion 28 at the lower end of a shaft 29. A shaft 29 is, of course, located at each end of the frame, and these shafts are rotatably mounted in bearing brackets 30 carried by the end portions of the frame. The shafts 29 project upwardly above the frame and at their upper ends are provided with worms 31 which mesh with worm gears 32 at the outer ends of shafts 33 which extend longitudinally of the upper bars 3 of the frame sections and are rotatably mounted in bearings 34. These shafts 33 carry beveled gears or pinions 35 at their inner ends which are adapted to mesh with the beveled teeth of the gear plate or disk 36 secured rigidly upon the post 15 of the drum. From an inspection of Fig. 1, it will be readily seen that, when the drum is rotated by means of the handles 19, rotary motion will be transmitted from the drum to the rollers 21 and since the cable extends between the rollers 21 and 22 it will be easily fed into and out of the frame by the rollers 21 as well as being guided in its movement. The gears and pinions must, of course, be so proportioned that the rollers 21 will feed the cable at the proper rate of speed in comparison to the speed at which the cable is wound onto or off the drum. Below the gear disk 36 the post carries a ratchet wheel 37 adapted to be engaged by a pawl 38 so that rotation of the drum to unwind the cable may be prevented. The pawl may, of course, be moved out of engagement with the ratchet wheel so that the cable may be unwound from the drum when necessary.

When this device is in use, one end of the cable is secured to a tree or stake driven into a roadway and the other end of the cable is attached to the axle of the automobile which is to be extracted. The drum is then rotated through the medium of the handle bars and as the drum is rotated the cable is wound upon the drum. A pulling action will, therefore, be exerted which will cause the automobile to be extracted from the mud-hole in which it has become mired. After the automobile has been extracted from the mud-hole, the cable will be released from the axle and stake or other permanent support to which it has been attached and the hasps 8 may be released from the keepers 9 so that the frame may be folded into a compact mass. The rod 20 will not, of course, be driven firmly into the ground as it must be moved along the ground as the cable is wound upon the drum.

Having thus described the invention, I claim:

1. A device of the character described comprising a frame including companion sections having their inner ends hingedly connected, a drum rotatably mounted between the inner ends of said frame and having a portion projecting externally thereof, means carried by the projecting portion of said drum for rotating the same, guide rollers carried by the outer end portions of said frame for engaging portions of a cable led into the frame and wound upon the drum, shafts rotatably carried by the outer ends of said frame sections and having gear connection with said rollers, a gear carried by the projecting portion of said drum, and rotary shafts extending longitudinally of the frame sections, the last mentioned shafts being rotated from the gear of said drum and connected with the first mentioned shafts to impart rotary movement thereto when the drum is rotated.

2. A device of the character described comprising a frame including companion sections hingedly connected and adapted to be swung into and out of alignment, means for releasably holding said frame sections in alignment, the adjacent ends of said frame sections being formed with recesses cooperating to provide bearings when the frame sections are aligned, a drum in said frame having portions adapted to fit in said bearings to rotatably mount the drum, and means for rotating said drum.

3. A device of the character described comprising a frame including companion sections hingedly connected and adapted to be swung into and out of alignment, means for releasably holding said frame sections in alignment, the adjacent ends of said frame sections being formed with recesses cooperating to provide bearings when the frame sections are aligned, a drum in said frame having portions adapted to fit in said bearings to rotatably mount the drum, guide rollers rotatably mounted upon the outer end portions of said frame sections and adapted to engage portions of a cable wound upon the drum and extending from the frame, means for rotating said drum, and means for transmitting rotary motion from said drum to said rollers.

4. A device of the character described comprising a frame including companion sections hingedly connected and adapted to be swung into and out of alignment, means for releasably holding said frame sections in alignment, the adjacent ends of said frame sections being formed with recesses cooperating to provide bearings when the frame sections are aligned, a drum in said frame having portions adapted to fit in said bearings to rotatably mount the drum, guide rollers rotatably mounted upon the outer end portions of said frame sections and adapted to engage portions of a cable wound upon the

drum and extending from the frame, means
for rotating said drum, a gear carried by
said drum, shafts rotatably carried by said
frame sections and having geared connec-
tions with said rollers, and other shafts ro-
tatably carried by the frame sections and ex-
tending longitudinally of the frame and

having geared connections with the last-
mentioned shafts and at their inner ends pro-
vided with gears adapted to mesh with the ¹⁰
gear carried by said drum when the frame
sections are alined.

In testimony whereof I affix my signature.
WILLIAM A. BRIGHTMAN. [L. s.]
